UNITED STATES PATENT OFFICE

105,441

DESIGN FOR A BIER PIN SUPPORT FOR HEARSE

Earl L. Schofield, Freeport, Ill., assignor to Hen-
ney Motor Company, Freeport, Ill., a corpora-
tion of Delaware

Application October 26, 1936, Serial No. 65,518

Term of patent 14 years

To all whom it may concern:

Be it known that I, Earl L. Schofield, a citizen
of the United States, residing at Freeport, in the
county of Stephenson and State of Illinois, have
invented a new, original, and ornamental Design
for a Bier Pin Support for Hearses, of which
the following is a specification, reference being
had to the accompanying drawing forming part
thereof.

In the drawing:

Figure 1 is a perspective view of the bier pin
support for hearses, showing my new design;

Fig. 2 is a side view of the support;
Fig. 3 is a plan view of the support, and
Fig. 4 is a front view.

In all of these views, the stippling shows con-
trasting color.

I claim:

The ornamental design for a bier pin support
for hearses, substantially as shown and described.

EARL L. SCHOFIELD.
